MAGNETIC TAPE UNIT

Melvin Rudin, Palo Alto, Calif., assignor to Datel
Corporation, McLean, Va.

Filed Nov. 4, 1970, Ser. No. 25,827

Term of patent 14 years

Int. Cl. D14—02

U.S. Cl. D26—5

FIG. 1 is a perspective view of a magnetic tape unit showing my new design;

FIG. 2 is a top plan view thereof;

FIG. 3 is a front end view;

FIG. 4 is a side elevational view;

FIG. 5 is a rear end view; and

FIG. 6 is another side view thereof.

I claim:

The ornamental design for a magnetic tape unit, as shown.
